CLAIM

The ornamental design for a blade disposal box, as shown and described.

DESCRIPTION

FIG. 1 shows a perspective view of the blade disposal box. FIG. 2 shows a top elevation view thereof.

FIG. 3 shows a bottom elevation view thereof.

FIG. 4 shows a right side elevation view thereof.

FIG. 5 shows a left side elevation view thereof.

FIG. 6 shows a front elevation view thereof; and,

FIG. 7 shows a rear elevation view thereof.

The broken lines shown in the drawings represent environmental effects or potential embodiments and do not form any part of the claimed design.
